UNITED STATES PATENT OFFICE.

JOSEPH A. BULLOCK, OF CENTRAL BRIDGE, NEW YORK.

STANCHION.

1,330,166.

Specification of Letters Patent. Patented Feb. 10, 1920.

Application filed January 20, 1919. Serial No. 272,139.

To all whom it may concern:

Be it known that I, JOSEPH A. BULLOCK, a citizen of the United States, residing at Central Bridge, in the county of Schoharie and State of New York, have invented certain new and useful Improvements in Stanchions, of which the following is a specification.

This invention relates to animal husbandry, and more especially to stanchions employing a stop lock; and the primary object of the same is to produce a stanchion having means to prevent it from rotating when it is open.

Other objects are to produce improved latching mechanism for holding it closed and actuating mechanism for opening and closing the yoke bars. Details are set forth below, and attention is drawn to the drawings, wherein—

Figure 1 is a front elevation of the stanchion open and

Fig. 2 is an edge view thereof.

Fig. 3 is an inverted perspective detail of the cap plate.

Fig. 4 is a vertical central section.

Fig. 5 is a central transverse section of the same in a closed condition.

Fig. 6 is a perspective detail of one of the latches.

Fig. 7 is a detailed sectional view taken on the line 7—7 of Fig. 4.

A base 1 has a supporting bolt or pin 2 pivotally mounted in a step bearing 3, and to the sides of the base at 4 are pivoted upright bars 5 preferably lined on their inner faces as at 6. These bars are of metal and of U-shape in cross section, and their upper ends are turned inward toward each other into what I will call shoulders 7, each bearing a triangular catch 8 whose abrupt face is disposed outward, each shoulder also having a headed pin 9 near its extremity and depending therefrom.

Mounted in an overhead support 10 is a pendant bolt 11 squared at its upper part as at 12, and mounted non-rotatably on the squared portion is a plate 13 which is flat on its lower face except for a pair of oppositely disposed radial grooves 14. Mounted on the bolt beneath the squared portion is a rotatable head block 15, to opposite sides of which at 16 are pivoted locking arms 17 each having its outer end turned downward and pivotally supporting a weight 18 at such point that it travels over

the angle between the upright portion of a yoke bar and its shoulder 7 when said bar is swung inward. This permits the outer end of the arm 17 to descend, but when the yoke bar is swung outward and the weight travels up in the channeled bar and over said angle near its pivot 16 each arm carries a knob 19 which when the arm rises, engages one of the grooves 14, and thereby the head is locked against rotation with respect to the cap plate. It follows, therefore, that the stanchion may not rotate when its bars are open.

The spreader mechanism for said bars 70 consists of a double lever 20 pivoted on the lower end of the bolt 11, a link 21 pivoted at 22 to the end of the lever, and a link 23 pivoted at 24 to the outer end of the link 21 and mounted on a vertical pivot 25 which connects it with one of the bars 5. A spring 26 surrounds the lower end of the head 15, one end 27 engaging the lever and the other end engaging a guide yet to be described, so that the normal tendency of the spring 80 is to spread the upper ends of the yoke bars and open the same. Yet when either yoke bar is moved inward, the spreader mechanism causes the simultaneous movement of the other yoke bar, and therefore 85 in order to close the stanchion, it is necessary to move only one of the yoke bars inward.

A guide 30 is secured at its midlength to the head 15 and extends on both sides of the same as perhaps best seen in Fig. 1 its arms being of a shape and size to receive the shouldered upper ends of the yoke bars 5 when the latter are moved inward, and in the bottom of said guide are slots 31 in 95 which the headed pins 9 travel. As this guide is fast on the head, and as the yoke bars move at their upper ends within the guide, it follows that when the stanchion is turned from side to side on its supporting 100 pin 2, the guide and the head rotate on the bolt 11 which stands in alinement with the pin 2. As the stop locking arms are pivoted to the head, they must also turn with it. This is permitted when the stanchion is 105 closed and the arms are in their lower position as seen in Fig. 4, because their knobs 19 are out of engagement with the grooves 14 in the cap plate; but as soon as the stanchion is opened and the arms are raised, 110 they can no longer turn and the head and guide are also prevented from rotation upon

the bolt 11. Therefore, at this time, the bars 5 cannot swing on their vertical pivot.

The latching mechanism consists of a pair of L-shaped latches 40, each pivoted at its angle upon respective arms of the guide 30 at 41 and each having in its upper arm a slot 48 to receive the tip of the catch 8. The lower arms of the two latches are connected at the rear side of the stanchion by a contractile spring, as shown at 42 in Fig. 5 whose action tends normally to draw the upper arms downward and engages their slots with the catches. On the front of the stanchion a pair of levers 43 are pivoted at 44 to the guide 30, their lower ends being connected by links 45 with the lower arms of the latches, and their upper portions moving under a guide 46 and being bent outwardly and carrying thumb pieces 47. 20 When the latter are grasped and moved toward each other, the lower ends of the levers are swung outward and the links 45 move the lower ends of the latches outward. The result is that their upper arms disengage the catches 8 and the bars 5 are free to move outward. As they do so the weights 18 rise and slots with which they are provided pass astride the catches 8 as will be clear. When the stanchion is closed and the 25 bars 5 again move inward, the catches automatically engage the latches, and the same are maintained in such engagement until the device is manually unlatched by the operator compressing the thumb pieces 47. 30 Therefore, the animal locked in the stanchion has freedom of movement of the head and shoulders while the stanchion is closed, but the latter must be set directly at right angles to the length of the stall before it can be 35 opened either to release the animal or to lock an animal therein.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope 45 of the appended claims.

Having thus fully described my invention, what I claim as new and desire to secure by Letters Patent is:—

1. In a stanchion, the combination with a base and a superposed block mounted on alined pivots, yoke bars pivoted at their lower ends to the base and having their upper ends shouldered and inturned, and latch mechanism for connecting said ends 55 with the head block when the bars are closed; of a non-rotary cap plate above said block and having grooves in its lower face, locking arms pivoted to opposite sides of the block and having knobs adapted to 60 engage said grooves when the arms are 65

raised, and means for raising their outer ends when the yoke bars are swung open.

2. In a stanchion, the combination with a base and a superposed block mounted on alined pivots, yoke bars pivoted at their lower ends to the base and having their upper ends shouldered and inturned, and latch mechanism for connecting said ends with the head block when the bars are closed; of a non-rotary check plate above 70 said block and having grooves in its lower face, locking arms pivoted to opposite sides of the block and having knobs adapted to engage said grooves when the arms are raised, and weights pivoted to the outer 75 ends of the arms and adapted to ride over the shoulders of the bars as said arms are swung outward and inward.

3. In a stanchion, the combination with a base and a superposed block mounted on alined pivots, a pair of yoke bars pivoted at their lower ends to said base and having their upper ends channeled and shouldered and bent inward toward each other, catches 85 carried by said inturned ends, a channeled guide carried by said head block and within which said inturned ends slide, coacting elements on each end and each arm of the guide for limiting the movement of the end, latches carried by the arms of the guide for 90 engaging said catches, and manually operable mechanism for tripping the latches; of locking arms pivoted at their inner ends to said head block and with their outer ends 95 engaging said yoke bars, and means engaging said arms when raised to prevent the 100 rotation of the head block.

4. In a stanchion, the combination with a base and a superposed block mounted on alined pivots, a pair of yoke bars pivoted at their lower ends to said base and having their upper ends channeled and shouldered and bent inward toward each other, catches carried by said inturned ends, a channeled guide carried by said head block and within 110 which said inturned ends slide, latches carried by the arms of the guide for engaging said catches, and manually operable mechanism for tripping the latches; of locking arms pivoted at their inner ends to said 115 head block and with their outer ends engaging said yoke bars, and a non-rotary cap plate above said head block having grooves with which said arms engage when the same are raised.

5. In a stanchion, the combination with a base and a superposed block mounted on alined pivots, a pair of yoke bars pivoted at their lower ends within said base and having their upper ends inturned and carrying depending pins; and a channeled guide carried by said head block and receiving said inturned ends, the bottom of the arms of said guide having slots receiving 125 said pins for limiting the movement of 130

the yoke bars; of latch mechanism including latches for holding said yoke bars in set position, means for tripping the latches, and a spring actuated spreading mechanism for opening the yoke bars when unlatched.

6. In a stanchion, the combination with a base and a superposed block mounted on alined pivots, a pair of yoke bars pivoted at their lower ends within said base and having their upper ends inturned and carrying depending pins, and a channeled guide carried by said head block and receiving said inturned ends, the bottom of the arms of said guide having slots receiving said pins for limiting the movement of the yoke bars; of triangular catches carried in the arms of said yoke bars, right-angular latches pivoted at their angles to the arms of said guide and having slots to be engaged by the tips of said catches when the bars are closed, a spring connecting the lower arms of said latches for maintaining said engagement with the catches, a pair of levers pivoted to said guide, connections between their lower ends and the lower arms of the latches, and thumb pieces on their upper ends, for the purpose set forth.

10 7. In a stanchion, the combination with a base and a superposed block mounted on alined pivots, a pair of yoke bars pivoted at their lower ends within said base and having their upper ends inturned and carrying

15 pins for limiting the movement of the yoke bars; of triangular catches carried in the arms of said yoke bars, right-angular latches pivoted at their angles to the arms of said guide and having slots to be engaged by the tips of said catches when the bars are closed, yielding means for maintaining such engagement, and manually operable mechanism for overcoming said means and tripping the latching mechanism.

20 8. In a stanchion, the combination with a base mounted on an upright pivot, a bolt pendant from an overhead support in line with said pivot, a head block carried by the bolt, and a channeled guide carried by the head block; of a pair of yoke arms pivoted at their lower ends to said base and having their upper ends inturned and sliding in the arms of said guide, latching mechanism between said ends and guide for holding the yoke bars closed, a double lever pivoted on the lower end of said bolt, link mechanism connecting its ends with the respective yoke bars, and a spring normally 55 turning said lever to open the yoke bars, as described.

25 In testimony whereof I affix my signature in presence of two witnesses.
